UNITED STATES PATENT OFFICE.

HENRY AUCHU, OF EMPORIUM, PENNSYLVANIA.

SHELL-CLOSING MACHINE.

1,058,522.

Specification of Letters Patent.

Patented Apr. 8, 1913.

Application filed October 13, 1911. Serial No. 654,505.

To all whom it may concern:

Be it known that I, HENRY AUCHU, a citizen of the United States, residing at Emporium, County of Cameron, and State of Pennsylvania, have invented certain new and useful Improvements in Shell-Closing Machines, of which the following is a specification.

This invention relates to shell closing machines.

My object is to provide a shell closing machine of simple, inexpensive and durable construction which will be rapid and safe in operation, by which filled paper cartridges 15 or shells containing explosive may be closed or crimped in a new manner.

The invention has for a further object the provision of novel means for holding the shell and for releasing it at will; novel 20 means by which a shell of any diameter may be held by the machine and closed or crimped; novel shell closing or crimping mechanism adapted to form a new kind of fold or closure for the shell, and other novel 25 instrumentalities, rendering the machine rapid and safe in operation.

The shell closing or folding means is susceptible of use on other types of machine than that set forth in the following 30 description and shown in the drawings, and I, therefore, consider the shell closing means as constituting an invention in and of itself; similarly, other features of the invention are susceptible of changes and modifications and 35 the present disclosures are to be deemed as explanatory rather than restrictive of the invention. Furthermore, the shell closing means is susceptible of modification and I lay claim to all changes therein coming 40 within the spirit and scope of the invention in that particular respect.

In the accompanying drawings:—Figure 1 is a perspective of the invention with certain parts broken away; Fig. 2, a side elevation; Fig. 3, a vertical section through the shell holder and the shell closing means; Fig. 4, a plan view looking down on the shell holder; Fig. 5, a perspective detail of one of the shell holding blocks; Fig. 6, a longitudinal section through the shell closing means; Fig. 7, an end view thereof; Fig. 8, a perspective of the plunger for the shell folding means; Fig. 9, a perspective of the shell folding means; and Fig. 10, a perspective of the folded end of the shell.

The base 1 may be supported on a table or

other suitable support, below which is a hinged treadle 2 for depression by the foot of the operator whose hands are thus left free for placing and removing the shells. 60 The connections of the treadle with the machine appear fully hereinafter.

Mounted upon the base 1 is the shell holder which consists of a fixed member or leaf 3 and a movable member or leaf 4 which is hinged at 5 to an upright 6. The members 3 and 4 are provided with shell holders 7 and 8. These may be permanently carried by said members, but they are preferably removable so that holders having openings 9 of the proper size may be substituted according to the diameter of the shell which is to be closed. These removable holders may have any suitable connection with the members 3 and 4, but they are preferably 75 provided with a dove-tailed tongue 10 adapted for reception in a corresponding vertical mortise in the members 3 and 4 and to rest upon a shoulder 11. One of these holders is shown in detail in Fig. 5, and the 80 manner in which they are carried by the members 3 and 4 will be clear from Fig. 4. The shell 12 is adapted to rest upon the base 1 and to be received in the grooves 9 of the holders 7 and 8 and to be firmly, yet easily, 85 grasped by said holders.

The shell 12 is of paper and of a type commonly employed for holding dynamite or other explosives, the lower end of the shell having first been closed in any preferred manner, and the explosive then filled within the shell to within a short distance of its upper end, whereupon the open end of the shell is ready for folding or closing. The shell shown in Figs. 1 and 3 has its upper end shown partially folded or creased to illustrate how it appears after it has been acted upon by the crimping part of the folding mechanism of the present invention, but when placed in the machine, its upper end is 95 completely open or tubular.

Carried by the member 3 is a roller 13, suitably journaled. Extending over this roller and through a slot 14 in the member 3 and crosswise of the holder, with its end 105 15 passed through a slot in the member 4 and secured to said member at 16, is a strap, cord or other suitable flexible member 17, which has a coil spring 18 connecting it to the treadle 2, the purpose of which is to 110 cause the hinged member 4 to close and grasp the shell 12 when the treadle is de-

pressed, the spring 18 permitting further depression of the treadle after the holder is closed, to cause the shell closing means to fold the end of the shell. A spring 19 interposed between the members 3 and 4, tends to normally open said members so that a shell may be readily inserted between the holders 7 and 8, and upon the release of pressure from the treadle 2, the members 10 automatically open to permit the closed or folded shell to be removed. Pivoted to the upright 6 is an arm 20 which extends lengthwise and over the shell holding devices. Depending from and secured to the 15 arm 20 by a removable pin 21 is a center folding plunger 22 whose lower end is of the form shown in Fig. 8, being provided with a plurality of longitudinally extending grooves or channels 23 and having a flat 20 lower end 24 through which said channels open.

Referring to Figs. 3, 6, 7 and 9, 25 represents a tubular crimpler which is telescoped over and slidable on the lower end of the 25 plunger, being loosely connected thereto and suspended therefrom by a pin-and-slot fastening and guide 26 which, while holding the parts in the position shown in Figs. 3 and 6, permits the plunger to continue its 30 downward movement after the arrest of the crimpler 25. The mouth of the crimpler is of tapered or bell shape, as shown at 27, and is preferably provided with an annular grooved terminus 28 at its upper end. Arranged preferably radially of the crimpler and disposed inside of it, are the folders 29 which are relatively thin and whose planes extend lengthwise of the crimpler. The lower edges 30 of these folders are 35 beveled or inclined. The crimpler 25 is received within a head 31 and the flange 32 of the crimpler bears against the under surface of said head. The head 31 is carried by a vertically movable slide 33 whose lower 40 part slides in a guide 34 (Fig. 2) and is sustained by a spring 35 bearing on the base 1. Rising from the head 31 is an upright 36. The upper ends of the slide 33 and the upright 36 are provided with slots 45 and 38. The slide 33 has an abutment or 45 stop 39. A removable pin 40 which passes through the arm 20, is adapted to slide in the slots 37 and 38. Interposed between the head 31 and the arm 20 and surrounding the plunger 22, is a coil spring 41. Secured to the arm 20 is an upright rod 42 which passes through an opening 43 in the treadle 2 and is provided with a head or an adjustable nut 44 which normally lies some 50 distance below the treadle 2 so that it will not be engaged thereby when the treadle is first depressed.

Normally the holder is kept open by the spring 19, the treadle being then up. The 55 operator places a filled shell whose upper

end is open in the holder and then depresses the treadle 2, in doing which the strap 17 pulls the member 4 toward the member 3 and the holder 7, in conjunction with holder 8, secures the shell in the position shown 70 in Figs. 1 and 3, but immediately after this operation, continued downward movement of the treadle 2 causes it to engage the head or nut 44 and the rod 42 is then drawn downwardly, the spring 18 yielding to permit such further descent. The downward movement of the rod 42 pulls down the arm 20 and the arm being connected to the slide 33, the said slide and the head 31 move downwardly together. The engagement of 75 the head 31 with the shoulder 32 on the crimpler causes the latter to be positively pressed over the open end of the shell or cartridge 12, whereupon the bell or conical mouth 27 tends to close the shell and at the 80 same time the folders 30 form the creases in the shell, as appears in Figs. 1 and 3. The head 31 and crimpler 25 having been arrested by the resistance of the filled shell, after partially closing the shell as above 85 indicated, the arm 20 is allowed a further downward movement by reason of the travel of the member 40 in the slots 37 and 38, in opposition to the sustaining tendency of the spring 41. The plunger 22 being fixed to 90 the arm 20, slides down within the arrested crimpler 25, the pin-and-slot connection 26 permitting this, and the flat end 24 coming in contact with the crimped and folded 95 end of the shell, presses down and depresses the folds and completes the closure which then appears as shown in Fig. 10, in which the folds 45 overlap each other and the plane of said folds is below the end of the shell, there being provided a circular bead 100 105 46 which is facilitated in being formed by the provision of the annular channel 28 which is of greater diameter than the flange for that purpose. On the release of the treadle 2, the spring 19 opens the member 4 and the spring 35 raises the slide 33 and all the parts are carried upwardly to normal position. The closed shell 12 is then removed by the operator and another shell 110 put in its place. These operations are carried on very rapidly and easily with absolute safety.

The folded or closed end of the shell constitutes a new invention which I claim in a separate application. If the cartridge is 115 paraffined after closing, owing to the character of the closure shown in Fig. 10, as formed by this machine, the cartridge is rendered waterproof.

The folding and crimping mechanism may 120 be used on another machine for closing the end of the shell before the explosive is filled therein and said closing mechanism constitutes a new invention by itself.

I wish it understood that the number 130

of the folders 29 and of the grooves or channels 23 may be increased or diminished to form a greater or lesser number of folds 45 than shown as may be desired or found 5 convenient, and further, that the operative parts of the machine may be arranged to fold or crimp the end of the shell when in a horizontal or any other position than a vertical one.

10 Having thus described my invention, what I claim as new and desire to secure by Letters Patent, is:—

1. In a shell closer, the combination with a crimper having a concavity adapted to receive the end of the shell, said crimper having internal folders adapted to form crimps or creases in the shell stationarily disposed in the concavity, of a member movable in relation to the crimper adapted to form 20 and press down the folds of the shell.

2. In a shell closer, the combination with a crimper having a concavity adapted to receive the end of the shell, said crimper having internal folders adapted to form crimps 25 or creases in the shell stationarily disposed in the concavity, of a member movable within the crimper and provided with grooves or channels which receive the folders, said member being adapted to form and press 30 down the folds of the shell.

3. In a shell closer, the combination with a crimper having a concavity adapted to bend the end of the shell, and internal folders arranged and adapted to crease or crimp 35 the end of the shell, said folders having their ends inclined where they are adapted to engage the shell, of a folding member movable within the crimper and adapted to form the crimped end of the shell into folds and 40 to press said folds down.

4. In a shell closer, the combination with a crimper having a concavity adapted to bend the end of the shell, and internal folders arranged and adapted to crease or 45 crimp the end of the shell, said folders having their ends inclined where they are adapted to engage the shell, of a plunger movable within the crimper and provided with grooves or slots loosely receiving the 50 creasers and folders aforesaid and adapted to form and press down folds on the end of the shell.

5. A shell closer having a bell-shaped

crimper adapted for receiving the end of a shell and tapering or bending the shell end 55 and provided with means for forming creases in the bent end of the shell, and a plunger operating within the bell-shaped crimper adapted for forming folds on the creased end of the shell and for pressing 60 down said folds.

6. A shell closer having a bell-shaped crimper adapted for receiving the end of a shell and tapering or bending the shell end and provided with means for forming 65 creases in the bent end of the shell, and a plunger operating within the bell-shaped crimper adapted for forming folds on the creased end of the shell and for pressing down said folds, said bell-shaped crimper 70 and plunger being constructed and adapted to each other so that they will press in the folded end of the shell and provide an outer raised rim on said shell.

7. In a shell closing machine, the combination with a shell holder adapted to open and close, of a shell closer, a movable operating device, an operative connection between said operating device and the shell holder which is provided with a spring whereby it 80 may be extended after the shell holder has closed, and an operative connection between the operating device and the shell closer.

8. In a shell closing machine, the combination with a shell holder having relatively 85 movable parts, and spring means adapted for opening said shell holder, of a movable shell closer embodying a crimper and a plunger which are movable in relation to each other and are both mounted to move together as an entirety, a spring which keeps the plunger normally retracted, a spring which keeps the complete shell closing means normally retracted, an operating member, a connection between said operating member 90 and the shell holder embodying a spring and a flexible member, and an operative connection between the shell closer and the operating member.

In testimony whereof, I hereunto affix 100 my signature in presence of two witnesses.

HENRY AUCHU.
